PROCESS OF TREATING COAL TAR CONTAINING A SMALL AMOUNT OF AMMONIUM CHLORIDE

William Tiddy, Manhasset, N. Y., assignor to
Allied Chemical & Dye Corporation, a corpora-
tion of New York

Application July 24, 1946, Serial No. 685,957

3 Claims. (Cl. 196—146)

1

The present invention relates to the substantially complete removal from coke oven tar of the small amount of water soluble salts chiefly ammonium chloride present therein.

Coke oven tars produced in coke oven batteries by the customary procedure involving cooling and washing coke oven gas usually with an aqueous medium, when distilled to produce desired tar distillates, such, for example, as creosote oil, naphthalene, tar acid and light oil fractions, invariably result in corrosion of the distillation equipment and plugging, due to ammonium chloride deposits, of the condensers associated with the distillation equipment. These difficulties are chiefly attributable to the small amount of ammonium chloride invariably present in coke oven tar. Various proposals have been advanced for eliminating the small amount, usually of the order of .2% by weight, of ammonium chloride present in coke oven tar to minimize corrosion of the distillation equipment and plugging up of the condensers when the tar is distilled. Of these proposals the one which has found widest commercial application is the washing of the tar with water frequently by pumping the tar into the top of a storage tank containing a layer of water under atmospheric pressure and temperature, the tar descending through the water layer and forming a tar layer underlying the water layer. After introduction of the desired batch of tar into the water layer, the tar and the water containing the dissolved salt are separately removed from the tank. This procedure is objectionable for numerous reasons, among which may be mentioned (1) it is relatively costly to carry out since it involves the use of one or more large storage tanks for the water layer through which the tar is passed and hence is capable of handling, per unit of time only a limited amount of tar; in order to handle the large volume of tar subjected to distillation in a tar distillation plant, a number of such tar washing units are required involving substantial plant investment, and (2) the procedure frequently results in a tar having a high water content, in excess of the water content of the tar originally processed, which tar, prior to distillation, requires a dehydration treatment materially increasing the cost of treating the tar.

It is an object of this invention to provide a process for removing substantially completely the small amount of ammonium chloride present in coke oven tar, which process is efficient in operation in that it effects substantially complete removal of the ammonium chloride, at least to an

2

extent so as to greatly minimize, if not completely eliminate corrosion of the distillation equipment and the plugging, due to ammonium chloride deposits, of the condensers when the tar is distilled; which process is capable of handling economically large quantities of tar to effect substantially complete removal of the small amount of ammonium chloride contained therein; which process requires relatively simple and inexpensive equipment for its practice and which process results in a tar product low in water, usually less than 2% by weight so that it can be distilled directly as it comes from the ammonium chloride removal process and does not require a separate dehydration treatment.

Other objects and advantages of this invention will appear from the following detailed description thereof.

In accordance with this invention substantially all of the small amount, usually of the order of .2% by weight of ammonium chloride present in coke oven tars is removed by continuously flowing a stream of the coke oven tar, continuously adding to this stream hot water or water and steam, introducing this mixture at a temperature within the range of about 200 to about 350° F. and under superatmospheric pressure, preferably within the range of about 50 to about 150 pounds per square inch gauge into a settling and separation zone, continuously flowing this mixture under the temperature and superatmospheric pressure conditions stated through the separation and settling zone where the ammonium chloride solution produced separates from the tar, forming a supernatant ammonium chloride solution resting on a tar layer, continuously removing the coke oven tar substantially free of ammonium chloride from this zone and separately removing the ammonium chloride solution from the zone. Preferably the ammonium chloride solution as well as the tar substantially free of ammonium chloride are removed continuously from this separation and settling zone maintained under superatmospheric pressure and at the elevated temperature above indicated; if desired, however, the ammonium chloride solution may be removed from the separation and settling zone intermittently, i. e., at predetermined intervals.

Operating in accordance with the process of this invention it has been found the ammonium chloride content of coke oven tar has been reduced from .2% by weight to .015% by weight and that the tar removed from the separation and settling zone contains less than 2% water.

The process of this invention it will be noted usually results in a reduction of the water content of the tar (coke oven tars as produced and supplied to distillation equipment usually have a water content of from 2% to 8% by weight) as well as the substantially complete removal of the ammonium chloride content. In the treatment, however, of tars containing small amounts of water, for example, of the order of 2%, the process of this invention will not necessarily result in a reduction of the water content of the tar as compared with its water content prior to treatment, but will invariably produce a tar which contains no more water than the amount of water present in the tar originally subjected to treatment.

The amount of water mixed with the tar will depend on the capacity of the equipment in which the process is carried out, the ammonium chloride content of the tar, and the temperature and pressure conditions under which the settling and separation is effected. An amount in excess of that required to dissolve all of the ammonium chloride present in the tar should be employed. In general from 1 to 19 volumes of tar may be mixed with each volume of water, preferably about 4 volumes of tar are employed per volume of water. The rates of flow of the tar, water and steam are not critical factors and will depend upon the specific equipment in which the process is carried out and are so chosen as to subject the tar and aqueous medium to a time of treatment in the settling and separation zone hereinafter disclosed.

The time of treatment of the tar in the separation and settling zone will depend on the extent of this zone, the rate at which the tar and aqueous medium are introduced thereinto and the rate at which the tar and ammonium chloride solution are withdrawn therefrom. These factors should be so correlated that the time of treatment falls within the range of about 3 to about 12 hours, i. e., a time interval falling within the range of about 3 to about 12 hours elapses between the time a particle of tar and aqueous medium mixture enters this zone and the time the tar portion of this particle mixture is withdrawn therefrom. Preferably these factors are so correlated that the tar and aqueous medium mixture require about 8 hours to pass through this zone. Operating under the conditions above noted substantially complete removal of the ammonium chloride from the tar as the mixture flows through this zone is effected.

The invention will be further described in connection with the accompanying drawing which is a flow sheet of the process and shows diagrammatically apparatus suitable for carrying out the process.

Crude coke oven tar from supply tank 1 is drawn through line 2 by pump 3, preferably a steam pump. A line 4 leads from this pump to a heat exchanger 5, passes through this exchanger and communicates with a line 6 which leads into a separation and settling tank 7. Water flows through a line 8 having a manually operable valve 9 therein into a mixer 10 of any conventional type. Steam flows from a supply line 11 having a valve 12 therein into the mixer 10, the steam preheating the water to a desired temperature which is determined by the temperature control device 13 in the line 14 leading from the mixer 10 to the tar line 2. The temperature controller 13 is connected with the valve 12 to control the amount of steam supplied to the mixer 10

to preheat the water to any desired temperature depending upon the setting of the temperature controller 13.

A meter 15 in the by-pass line communicating with line 14 indicates the amount of water admixed with the tar; this amount being controlled by the valve 9.

Pump 3 is operated by steam supplied through line 16 leading from supply line 11 and having a valve 17 therein. Valve 17 is actuated by a pressure controller 18 located in line 6 at or near the inlet to tank 7; this pressure controller may be of any well known type and is set to maintain the tar water mixture entering the settling and separation tank 7 at a constant superatmospheric pressure, preferably within the range of 50 to 150 pounds per square inch gauge.

The tar water mixture from pump 3, as above indicated, flows through line 4 and then through the heat exchanger 5, or, if it is desired, through line 19 by-passing heat exchanger 5 directly into line 6 leading to tank 7. Flow through line 19 is controlled by valve 19'. A temperature controller 20 of any well known type is disposed at or near the inlet to tank 7 in line 6 and operates a valve 21 in line 22 leading from the steam supply line 11 to line 6. This temperature controller is set so as to maintain the tar water mixture entering the separation tank 7 at a constant temperature within the range of 200° to 350° F.

The separation tank 7 may be placed in a horizontal position, as diagrammatically shown in the drawings, or tilted from 7° to 20° from the horizontal to improve separation of the tar and ammonium chloride solution.

As the mixture of water and tar flows longitudinally through tank 7 it stratifies into two layers, the ammonium chloride solution forming the supernatant layer and the tar the lower layer. A level control instrument 23 of any conventional type at the discharge end of tank 7 effects actuation of pressure reducing valve 24 in line 25 through which the ammonium chloride solution is withdrawn from the tank. Tar withdrawal line 26 leads from the base of tank 7 and has therein a pressure reducing valve 27 which is actuated by flow controller 28 of any conventional type. Line 26 has one branch passing through the heat exchanger 5 and leads into a line 29 which communicates with tar storage tank 30, and another branch 31 which by-passes heat exchanger 5. Flow through the by-pass branch 31 is controlled by a manually operable valve 32. By-pass line 31 leads into the line 29 communicating with storage tank 30.

Controller 28 and the liquid level controller 23 are so set as to maintain an interface mixture of approximately 50% tar and 50% ammonium chloride solution at about the point in the separation tank 7 spaced approximately .7 of the length of the tank from the inlet thereto.

Line 25 leads into a tank 33 provided with a vent 34 and having a line 35 leading to sewer or other point of disposal for the ammonium chloride solution.

It will be noted that the present invention provides a continuous process for substantially completely removing the small amount of ammonium chloride present in coke oven tar which process is simple to carry out, and has a high throughput capacity. The process of this invention treats coke oven tar continuously to reduce the ammonium chloride content thereof to .015% or even lower and to produce a tar containing less

than 2% water, which tar can be fed continuously directly to the distillation equipment, greatly minimizing, if not completely eliminating, corrosion and condenser plugging up difficulties, due to ammonium chloride deposits, heretofore encountered in the distillation of coke oven tar.

The term "water" is used in the claims in its ordinary chemical sense to mean H_2O and includes water in the vapor phase, i. e., steam as well as vapor and liquid mixtures.

It is to be understood that this invention is not restricted to the present disclosure as variations may be made without departing from the scope of the invention.

What is claimed is:

1. A process of treating coal tar containing a small amount of ammonium chloride which comprises continuously flowing the tar, continuously adding water to the tar, introducing the resultant mixture under a superatmospheric pressure of at least about 50 pounds per square inch gauge and at a temperature within the range of about 200° to about 350° F. into a settling and separation zone and flowing the mixture through this zone while permitting the resulting ammonium chloride solution and tar to separate and removing tar substantially free of ammonium chloride from this zone.

2. A process of treating coke oven tar containing a small amount of ammonium chloride which comprises continuously flowing a stream of the coke oven tar, continuously adding a stream of water to the coke oven tar, introducing the resultant mixed stream under a pressure of from about 50 to about 150 pounds per square inch gauge and at a temperature of from about 200° to about 350° F. into a settling and separation zone, flowing this mixture through this zone while permitting the resulting ammonium chloride solution and tar to separate and while main-

taining the tar and ammonium chloride solution under said temperature and pressure conditions and removing tar substantially free of ammonium chloride from this zone.

- 5 3. A process of treating coke oven tar containing approximately .2% by weight of ammonium chloride which comprises continuously flowing a stream of the coke oven tar, continuously adding to the flowing stream of coke oven
 10 tar a flowing stream of hot water, continuously introducing the resultant mixture at a temperature of 250° to 300° F. and at a pressure of from 50 to 150 pounds per square inch gauge into a separation and settling zone, continuously flowing
 15 the mixture through this zone while maintaining the tar and ammonium chloride solution under said temperature and pressure to permit the tar and ammonium chloride solution to separate into two layers, the ammonium chloride solution forming the supernatant layer, continuously removing the coke oven tar substantially free of ammonium chloride from said zone and releasing the pressure thereon and continuously removing the ammonium chloride solution from
 20 said zone.
